AUTOGRAPHIC REGISTER

Dana W. Mox, Glenview, Ill., assignor to Uarco Incorporated, Chicago, Ill., a corporation of Illinois

Filed Sept. 20, 1960, Ser. No. 62,212

Term of patent 14 years

(Cl. D64—11)

FIG. 1

FIG. 2

FIG. 3

FIG. 4

FIG. 5

FIG. 1 is an isometric view of an autographic register embodying my new design;

FIG. 2 is a top plan view thereof;

FIG. 3 is a side elevational view;

FIG. 4 is a rear elevational view; and

FIG. 5 is a front elevational view thereof.

I claim:

The ornamental design for an autographic register, as shown.
